UNITED STATES PATENT OFFICE.

WILLIAM F. HELMOND, OF HARTFORD, CONNECTICUT, ASSIGNOR TO UNDERWOOD TYPEWRITER COMPANY, OF NEW YORK, N. Y., A CORPORATION OF DELAWARE.

TYPEWRITING MACHINE.

Application filed April 11, 1919. Serial No. 289,259.

To all whom it may concern:

Be it known that I, WILLIAM F. HELMOND, a citizen of the United States, residing in Hartford, in the county of Hartford and 5 State of Connecticut, have invented certain new and useful Improvements in Typewriting Machines, of which the following is a specification.

This invention relates to an improved 10 paper-guiding device for a typewriting machine, and is herein illustrated as applied to a platen frame adapted for use with a machine of the Underwood front-strike type.

An object of the invention is to provide 15 an improved adjustable guide for the side edge of the work-sheet, and means for supporting the same.

As herein disclosed, the invention provides 20 for the construction of such a guide, of a single piece of sheet-metal, whereby a substantial reduction of cost, as compared with that of guides previously in use, is effected. This construction also aids in eliminating noise. The body of the guide extends down- 25 wardly and forwardly, preferably lying directly in contact with the table or paper-shelf of the typewriter, and is provided, preferably at one edge, with an upturned flange or paper-guiding element, forming a 30 gage or guide for the side of the sheet. The guide is continued upwardly and rearwardly, and curved to form a flexible neck extending over the usual bead on the paper-shelf, and down beneath the same. The rear 35 end of said guide is preferably provided with a pair of offset ears having perforations therein, thus forming an attaching portion adapted to fit upon a rod of non-cylindrical form which may be described as D-shaped,

40 half round, or segmental in cross-section, and with a narrow spring tongue projecting from said guide, between said ears, and curving around said rod sufficiently to bring its extremity against the flat surface of said 45 rod, thus serving to hold the paper-guide against the front surface of the paper-shelf, and frictionally opposing accidental displacement of the guide along the shelf. The guide may be adjusted when desired by lifting the same slightly from the paper-shelf, and moving the same to right or left.

The supporting means for the paper-guide 50 may comprise the above-mentioned rod of segmental cross-section and a pair of brackets secured to the platen frame. For con-

venience, in assembling the parts, one of said brackets may be provided with a circular opening, into which said rod may be inserted, and the other bracket provided with a D-shaped opening, to receive a reduced end of said rod. Any suitable means, such as a screw, inserted into a threaded opening in the reduced end of the rod, may be used to maintain the same in position.

It will be seen that the paper-guide and 65 its mounting are simple, inexpensive and readily applied to the platen frame, and that the structure is such as to facilitate elimination of noise during the operation of the machine.

Other features and advantages will hereinafter appear.

In the accompanying drawings,

Figure 1 is a perspective view of the platen frame of an Underwood typewriting 75 machine, with my invention applied thereto.

Figure 2 is an end view, partly in section, of the structure shown in Figure 1.

Figure 3 is a perspective view, showing my improved paper-guide, and the guide- 80 bar on which it is mounted.

Figures 4 and 5 show the brackets in which the guide-bar is supported.

Figure 6 is a view, showing the guide-bar, with its center broken away, and also 85 showing the ends of said guide-bar.

Figure 7 is a plan view of part of the paper-table, with my invention applied thereto, parts being broken away, to show the underlying structure.

The usual cylindrical platen 1 is supported 90 in the platen frame by means of a shaft or axle 2, mounted in end frames 3, which are connected by a paper-shelf or table 4, having a bead 5, of the usual form, at one edge, 95 and preferably secured to a bar 7 and to said end frames by means of fastening devices, such as screws 8. Said end frames are also connected by means of a rod 9, fixed thereto.

The paper-shelf 4 is provided with a flat portion 10, at the rear, and a continuously arched portion 11, extending from said flat portion to the vicinity of the platen, the paper-shelf being connected at its forward 105 edge to the end frames of the platen frame by any desired means, such as inwardly extending projections 12 on the end frames, and screws or other fastening devices 13. Associated with the platen are the usual 110

pressure rolls 14 and a suitable guiding device 15 extending from the paper-shelf to the front of the platen.

Provision is also made of an edge guide 16, preferably of a single piece of sheet-metal, comprising a body portion having a flat portion 17, normally overlying the flat portion 10 of the paper-shelf, and an arched portion 18, forming a resilient neck curved over the bead at the rear edge of said paper-shelf and extending beneath the same. At the end of the arched portion or neck 18 upturned ears 19 are provided, having D-shaped or segmental-shaped openings 20, and a spring tongue 21 extends from the arched portion 18 between the ears 19. The flat portion of the guide 16 is provided with an upstanding flange or guide 22 preferably at one edge thereof. Passing through the D-shaped openings of the offset ears 19 is a D-shaped bar 24, having a flat surface 25 against which presses the spring tongue 21, referred to above. At one end said bar 24 is supported in a bracket 26, having a circular opening 26a of the same radius as the bar, and at the other end in a bracket 27, having a D-shaped or segmental-shaped opening 28 of smaller area than the cross-section of the bar, into which is fitted the reduced end 29 of said bar. The resilient neck portion 18 serves as spring means to press the flanged guiding portion 17 against the upper surface of the paper-table 4. The bar 24 may be maintained in position by any suitable means, and preferably is provided with a threaded opening 30, into which is fitted a screw 31.

It will be seen that portion 11 of the paper-shelf is continuously arched from the line of demarkation between said portion 11 and the flat portion 10, so as to avoid having any flat portion, and, consequently, to render the paper-table sufficiently stiff, and to avoid any tendency to become noisy during the operation of the machine. The forward edge of the edge guide 16 extends to said line of demarkation between the flat and arched portions of the paper-shelf, and, consequently, when the platen is turned back, the rear edge of the paper will be supported by the arched portion 11, so as to ride over the forward edge of the edge guide 16.

It will be seen that the extremity of the spring tongue 21 contacts with the rearward portion of the flat upper rearwardly-inclined surface 25 on said bar 24, and that it tends, therefore, not only to provide a frictional resistance to moving the edge guide along said bar, but also tends to turn the edge guide about said bar, so as to press the forward edge of the guide against the paper-shelf. Such turning movement of the edge guide may also cause the paper-guide to bind on the bar 24. When it is desired to adjust the position of the paper-guide, it

may be lifted slightly from the paper-table, and this movement, if not too great, will tend to remove the binding action between the paper-guide and the bar 24, and enable the paper-guide to be moved more easily. 70 Also such lifting of the paper-guide will avoid any unnecessary scratching of the paper-table.

The arrangement by which bracket 26 is provided with a circular opening and bracket 27 with a segmental opening facilitates placing bar 24 in the machine, for the round bar, from which bar 24 is made, is substantially of uniform cross-section, and therefore can be passed through the circular opening without difficulty, whereas, if the openings in both brackets were of the same form as the cross-section, any slight variation in the position of the flat surface would cause binding and might interfere with the placing of the forward end in the second bracket into which it is inserted. Obviously, the means for preventing the bar from turning can be placed at either end, greater rigidity being obtained when the bar is secured 90 against rotational movement at the end on which the edge guide is mounted.

Variations may be resorted to within the scope of the invention, and portions of the improvements may be used without others. 95

Having thus described my invention, I claim:

1. A one-piece paper-guide for the paper shelf of a typewriting machine, comprising a body portion having offset ears provided with openings of such shape as to prevent substantial rotational movement of said guide about a bar having a cross-section of the same general shape as said openings, said body portion being curved to extend 105 around the rear edge of the paper shelf, and being provided in the vicinity of said offset ears with a spring extension curved to extend in a direction around said bar with its end in contact therewith. 110

2. A paper-guide for the paper shelf of a typewriting machine, comprising a body portion having offset ears on the end portion curved to extend around the rear edge of the paper shelf, said ears being provided 115 with openings, each having a straight line forming a part of its perimeter, to permit said ears to be fitted over a supporting bar having a flat surface, and said body portion having a spring extension, the extremity of which is positioned to press on said flat surface, so as to tend to hold said guide against displacement along said bar, and to move said guide in a direction to cause its forward end to press against the paper shelf. 125

3. A paper-guide for the paper shelf of a typewriting machine, comprising a body portion provided at its forward end with an upstanding flange, the rearward portion of said guide being bent to extend around the 130

rear edge of the paper shelf and provided with offset ears and having openings therethrough, the perimeter of each of said openings including a straight line, to enable said 5 ears to fit over a bar having a flat surface, said rearward portion of said guide being also provided with a spring extension, having its end in position to contact with said flat surface.

10 4. A sheet-metal edge-guide for the paper shelf of a typewriting machine, comprising a flat portion adapted to co-operate with a corresponding flat portion of the paper shelf, and having an upstanding flange, a 15 portion of said guide extending from said flat portion, arched to pass over a bead at the edge of the paper shelf, two ears offset from sides of said arched portion, and having openings adapted to fit over a supporting bar, and a curved spring tongue extending from said arched portion at a point between said ears, and having its extremity in position to engage and press on said bar.

5. In a typewriting machine, in combination, a paper-table, a non-rotative supporting bar extending in spaced relation along the rear edge thereof and having a non-cylindrical cross-sectional form, and a

paper-guide having an attaching portion 30 slidably but non-rotatably directly connected with said bar, so that said bar holds said guide against substantial rotative movement, a body portion to rest against the face of said table, a paper-guiding element projecting upwardly from said body portion, 35 a resilient neck portion connecting said body portion with said attaching portion and serving as spring means to normally resiliently hold the former firmly pressed against the upper surface of said table, and 40 a spring tongue extending from said neck portion adjacent said attaching portion and having an end normally pressed into frictional contact with the non-cylindrical surface of said bar, so as to tend to hold said 45 guide against displacement along said bar, the surface of contact between said tongue and bar being so related with respect to the center of attachment between said guide and said bar as to aid in holding said guide 50 pressed firmly against said table.

WILLIAM F. HELMOND.
